INVENTOR.

Joseph Laubser

United States Patent Office.

JOSEPH LAUBSER, OF MILWAUKEE, WISCONSIN,

Letters Patent No. 101,278, dated March 29, 1870.

IMPROVED RATCHET DRILL.

The Schedule referred to in these Letters Patent and making part of the same.

To all whom it may concern:

Be it known that I, JOSEPH LAUBSER, of the city and county of Milwaukee, and State of Wisconsin, have invented a new and useful Improvement in Ratchet Drills; and I do hereby declare that the following is a full, clear, and exact description thereof, which will enable those skilled in the art to make and use the same, reference being had to the accompanying drawing forming part of this specification, in which—

Figure 1 is a perspective view of my invention.

Figure 2, an end view.

Figure 3, a top sectional view.

Similar letters of reference in each of the figures indicate corresponding parts.

Nature and Object of the Invention.

The nature of my invention is to provide for turning the drill when the handle is carried in either direction.

A is the working-handle of the drill.

B, a short handle.

CC, bars that connect this short handle to the working-handle.

D D, the frames which hold the wheels.

E, rivets which hold the bars C in position.

F, the drill-stock.

G G, pins, which hold the frames D D together.

H H, pins, which hold the pawls.

I, pin, on which the second set of wheels moves.

K K, cog-wheels, meshing together on the drill-stock F and pin I.

L L, ratchet-wheels secured to the drill-stock F and pin I.

M M, ratchets, secured to the handles A and B.

N N, springs, which hold the pawls to duty.

This ratchet drill, by working the handle A back and forth, keeps the drill-stock in a continuous motion, and thus performs double duty.

Claim.

I claim as my invention—

The combination in a ratchet drill of the handles A and B, links C, frames D D, stock F, pins G and I, cog-wheels K K, ratchet-wheels L L, pawls M M, and springs N N, constructed substantially as described, and arranged to operate in the manner and for the purpose set forth.

JOSEPH LAUBSER.
